RAILROAD TIE PLATE SHIM

Tom W. Saul, Tucson, Ariz.

Application March 22, 1955, Serial No. 495,987

6 Claims. (Cl. 238—309)

This invention relates generally to railway rail mounting devices and is concerned more particularly with an improved means for securing the tie-plate to the tie and restricting both horizontal and vertical movements of the plate with reference to the spikes and to the tie below the plate into which the spikes are driven.

When mounting railway rails, it is customary to employ tie-plates which are secured to the upper surfaces of the spaced ties, said plates being of a width substantially equal to the width of the ties upon which they are mounted. Such plates are equipped with ribs or shoulders to properly position the rails supported thereby. Conventional spikes are driven downwardly through holes in the tie-plates and into the ties to secure the plates to the ties, the heads of certain of these spikes overlying the longitudinal edges of the rail base to retain the rail within the recess between the ribs or shoulders.

The tie-plates referred to above are made as rolled steel stock, the individual plates being sheared from strips of the rolled stock in lengths corresponding to the widths of the ties with which they are to be used. Following this shearing operation, each tie-plate is provided with the required number of square holes through which the spikes are to be later driven. These square holes are designed to be of slightly greater cross-section than the spikes and to have their corners rounded to fit arcs of circles of small radius. These rounded corners result in small vertical fillets at the corners of the holes, the result being that less clearance is provided between the corners of the spikes and the sides of the holes in the plates.

The holes in the plates are punched through from the under sides of the plates to the rail-supporting upper sides of the plates. As the punch proceeds through the metal in the forming of each of these holes, the cross-section of the hole tends to increase and, as the punch approaches the upper side of the plate, the metal ruptures and is displaced ahead of the punch. This results in an irregularly tapered hole with rough and uneven sides, in cross-section notably larger than the cross-section of the punch and in depth variable according to the thickness of the metal through which the hole is being punched.

It is well known in railroad engineering that such discrepancy in the hole sizes frequently results in insecure mounting of the tie plate in that play may occur between the spikes and the sides of the holes to cause looseness therebetween.

Such looseness permits the tie-plates to move both horizontally and vertically under the rails as the latter are moved by the travel of the rolling stock over them and such movements of the plates result in lifting and pressing of the plates against the spikes and thereby loosening and displacing the spikes in the ties and permitting abrasion of the ties by the plates.

Until recently tie-plates were equipped with holes for spikes to be driven only contiguous to the rail bases. Tie plates of current design are generally made longer and are equipped with holes located toward the outside corners of the plates and distant from the rail bases. Spikes are

2

driven into the ties through these holes to aid in restricting the movements of the tie plates relative to the ties. Primarily, however, their purpose is to guard against the vertical movements of the tie-plates and they are commonly termed "hold-down" spikes.

Since railroad operators employ very large numbers of the tie-plates for new tracks and as replacements in existing railways, it is important that the cost of the plates be maintained at a minimum. For this reason, the inaccurately punched square spike holes have been tolerated. In an effort to alleviate misfitting of the spikes in the holes, the spikes have been designed with a view toward more completely filling in the holes to compensate for the excessive clearance between the shank of the spike and the hole. The spikes, which are steel forgings, are provided with shanks, the upper ends thereof immediately beneath the heads being tapered to conform generally to the inclined sides of the spike holes. The spikes are driven to a position where the tapered portions of their shanks tend to fill in the spike holes of the tie-plate. However, while this expediency may help to alleviate the condition, it is not wholly satisfactory for the reason that a precision fit of the tapered shank in the hole is impossible due to the variations occurring in the holes and the rough, uneven condition of the hole surfaces. Consequently, while some progress has been made in this direction, the means relied upon is inadequate to meet the demands of present-day railroading involving the use of rolling stock of ever increasing speeds.

It is the primary object of the present invention to obviate the deleterious condition discussed above by providing means for more positively securing the tie-plate in place on the tie in a manner such that relative movement between the tie, spikes and rail-plate is very effectively resisted. This object is attained by providing means which insures a tight fit of the spike shank, substantially throughout its length, within the punched hole of the tie-plate so as to restrict any movement of the tie-plate relative to the spike.

Another object of the invention is to provide a means, in the form of a filler or shim of relatively thin metal which is inserted into a square punched hole of the tie-plate to provide a liner therefor, said filler element being of a thickness to take up the play or clearance between the sides of the hole and those of the spike driven therethrough. A related object is to provide a filler element which is angular to adapt its sides or legs to be positioned against right-angularly related sides of the spike hole so as to reduce the size of the hole in both directions, that is, to reduce the cross-sectional area of the hole to one which variably approximates the cross-sectional area of the shank of the spike. By this provision, when the spike is driven through the hole, the filler element, which is constructed from somewhat ductile metal, is compressed or flattened to cause it to be displaced more or less into the irregularities appearing in the sides of the hole, the metal thus wedging firmly between the sides of the hole and the spike to effect an extremely tight force fit which makes it most difficult to move the tie-plate and spikes relative to each other.

Another object of the invention is to provide a spike-holder element of the character referred to, which is easy to apply, the element being merely set into the hole, prior to insertion of the spike, with its sides or legs placed against the corresponding sides of the spike hole, the element having one or more stop ears which rest upon the upper surface of the metal surrounding the spike hole so as to retain the element against falling through the hole or being driven through the hole with the spike. A related object is to provide an element in which the ears or tabs are so located that the same element is adapted for use in either a spike hole located near the outer edge

of the tie-plate or at the thicker portion of the plate adjacent the rail seat where the spike is used to overlie the longitudinal edge of the base flange of the rail. In the latter case, one of the tabs may be engageable with and bendable by the head of the driven spike so as to serve as a spacer between the tie-plate and the head of the spike to limit downward movement of the head and thus provide slight clearance between this head and the rail to allow the latter to spring upwardly in response to the "wave motion" imparted to the rail by the rolling stock.

Another object of the invention is to provide a filler element or liner of the character specified which has angularly-related sides or legs, the intersecting portion or corner between the sides being provided with a slit extending downwardly from the upper end of the element to a point adjacent the lower edge of the element. By this provision, the sides of the element are adapted to bend or deform laterally, independently of each other, to conform to the inclined side of the spike hole in the tie-plate against which each side of the element is positioned. In addition, due to the vertical slit the occurrence of a solid thickness of the liner interposed between the corner of the spike and the fillet at the corner of the hole in the tie-plate is avoided so that driving of the spike downwardly through the spike hole is not unduly impaired.

A further object of the invention is to provide a liner of the type indicated having sides which are of such width that their free edges, remote from the slit, are positioned to clear the fillets at the corresponding corners of the spike hole so as to avoid obstruction to the passage of the corner of the spike as the latter is driven through the hole into the wooden tie.

Another object of the invention is to provide a filler element, shim or liner which is extremely simple in construction and one which is adapted for mass production as a sheet metal stamping so as to minimize the cost to the railroad operator, the added cost of using the liners in the track bed being almost negligible.

Further objects of the invention will appear from the following description and from the drawings which are intended for the purpose of illustration only, and in which:

Fig. 1 is a perspective view of a rail tie, tie-plate and spikes employed for supporting one of the rails of a rail-way track;

Fig. 2 is a plan view of the same, on a larger scale;

Fig. 3 is a cross-sectional view, taken on line 3-3 of Fig. 2;

Fig. 4 is a vertical sectional view, taken on line 4-4 of Fig. 3;

Fig. 5 is a cross-sectional view, taken on line 5-5 of Fig. 2;

Fig. 6 is a vertical sectional view, taken on line 6-6 of Fig. 5;

Fig. 7 is an enlarged, sectional plan view, taken on line 7-7 of Fig. 5;

Fig. 8 is a perspective view of one form of the filler element or liner;

Fig. 9 is a perspective view of another form of the filler element or liner; and

Fig. 10 is a perspective view of still another alternative embodiment of the filler element.

Referring first to Figs. 1 to 9 of the drawings, the present invention is herein illustrated as applied to use in connection with a conventional railway rail 20 having a base flange 21, an upstanding web 22 and a head 23. The rail 20 is supported by a plurality of hard wood ties 25, only one of which is illustrated. As is usual in railway structures, tie-plates 26 are secured to the upper surfaces of the ties 25, the rails resting directly upon these tie-plates.

Each tie-plate 26 has outer sloping portions 27, the inner ends of which terminate in rounded ribs 28 providing laterally-spaced longitudinal shoulders 29 between which the longitudinal edges of the rail base 21 are located to prevent lateral spreading of the track. The tie-

plate 26 is provided with a plurality of spike holes 30 and 31 punched through the metal from beneath the plate. The holes 30 are located in the outer sloping portions 27 while the other holes 31 are disposed at the ribs 28. As shown, these holes are square in cross section, the sides of the holes meeting in rounded corners or fillets 32. According to standard practice, the square holes 30 are punched through from the under side of the plate and due to the action of the punch as explained above, each hole 10 assumes a tapered contour with its sides diverging toward the upper side of the plate. Since the metal ruptures and is displaced ahead of the punch, the sides of the upper portion of the hole may slope outwardly at a greater angle, as shown in Figs. 3 to 6, and have rough, uneven 15 surfaces.

Each tie-plate 26 is secured against the upper surface of a tie 25 by means of conventional spikes 35 which are driven through the holes 30 and 31 and into the wooden tie 25. In accordance with standard practice, each spike 20 has a shank 36 of square cross sectional shape, the shank having a lower pointed end (Fig. 1) which facilitates driving the same into the tie 25. The spike 35 also has a head 37 of generally oval shape. As shown, the upper end 38 of the shank 36 immediately below the head 37 is 25 tapered to adapt it to conform somewhat to the irregularly tapered form of the hole 30 or 31 of the tie-plate 26.

It is intended that the upper end 38 of the shank 36 will fit snugly within the tapered hole 30 or 31 when the 30 spike is driven into the tie and thus wedge therein to provide a tight fit. However, due to inaccuracies in the 35 sizes and irregular taper of the holes 30, 31 and to the rough surfaces thereof, referred to above, what may first appear to be a tight fit is in effect a relatively loose one which invariably becomes even more pronounced as time goes on, this condition being aggravated by the lateral 40 stresses and strains imposed against the tie-plate by the rolling stock. When such looseness prevails, the tie-plate is permitted to move both horizontally and vertically under the rail as the latter is moved by the rolling stock traveling over the rail and such movements may result in lifting and forcing of the plate against the spikes to cause loosening and displacing of the spikes in the tie. This condition may be so extensive as to allow lateral 45 springing of the rail.

As previously indicated, it is the purpose of this invention to obviate this condition by providing an effectively tight fit of the spikes in holes of the tie-plate so as to minimize relative movement therebetween. In accordance 50 with the invention, this result is attained by utilizing filler or shim means within the holes. This means may consist of a filler element or liner 40 which is made as a simple stamping from sheet metal, preferably of a relatively soft, ductile nature.

As shown best in Fig. 8, each element 40 is simply a 55 sheet metal angle having right-angularly related sides or legs 41 and 42, the angle being slit vertically at the intersection of the sides, as shown at 42', with the slit or slot terminating at a short distance above the lower end of the element. The slot 42' preferably is of a width at 60 least equal to the chordal distance across a fillet 32 of the spike holes 30 or 31. The side 42 is somewhat longer than the side 41 and its upper edge portion may be curved slightly as shown at 43. The other leg 41 has an outwardly bent tab or ear 44 at its upper end. The 65 thickness of the sheet metal is an important consideration. Tie-plates currently in use commonly have spike holes specified to be $1\frac{1}{16}$ inch square, or $\frac{1}{16}$ inch larger than the $\frac{5}{8}$ inch spikes used therewith. This oversize is provided because of the presence of the fillets at the corners of the holes which are necessary to prevent rupture of the steel and breakage of the plates during the punching operation. It is important to note that the $\frac{5}{8}$ inch square spikes are frequently upset during the pointing operation 70 to be slightly over-size for some distance above their 75

points. Also, in the formation of the heads of the spikes, the shanks of the spikes are frequently up-set to oversize some distance below the tapered portions 38 of the upper shanks. For this reason, the thickness of each liner 40 must be somewhat less than the $\frac{1}{16}$ inch clearance indicated between the spike and the sides of the hole in the plate. For example, it has been found that a liner fabricated from 18 gauge sheet metal stock satisfactorily meets the requirements.

Assuming that the tie-plate 26 is in place upon the tie 25 and that the rail 20 is resting upon the tie-plate and has been aligned and gauged, to anchor the tie-plate and hold the rail in place, the following procedure is carried out. The workmen may first place the filler elements 40 in the square apertures 30 and 31 in the appropriate positions. In this respect, it is to be noted that in applying an element 40 to a spike hole 30, the wing 42 thereof is located at the side of the aperture which is nearest a longitudinal edge of the tie-plate, and the wing 41 is located at a side of the aperture which extends normal to said edge. On the other hand, when inserting an element 40 into a spike hole 31, the wing 41 is positioned to extend parallel to the longitudinal shoulder 29 of the tie-plate while the side 42 is caused to extend normal thereto. In either case, the tab or ear 44 of the wing 41 is adapted to rest upon the metal at the edge of the aperture 30 or 31 to limit insertion of the element downwardly thereinto.

With the filler elements thus placed in the spike holes 30 and 31, the pointed end of a spike is inserted through a hole into contact with the wooden tie 25, after which the spike is driven into the wood by means of a sledge or a spike-driving mechanism. During the initial driving action, the straight portion of the shank 36 slides freely through the aperture defined, in part, by the liner 40. During this initial driving, the tab 44 serves to prevent downward sliding of the liner in the hole. When the tapered portion 38 enters the tapered aperture 30 or 31, light binding action is created due to the fact that the wings or sides 41 and 42 reduce the effective area of the aperture 30 or 31 to a size which is substantially equal to, or slightly less than, the cross-sectional area of the tapered portion 38 of the spike shank 36.

The slit or slot 42' performs several important functions. For example, the slit allows one side of the liner to conform, independently of the other side, to the side of the hole in the tie plate against which it is positioned. It also provides that throughout its length a solid thickness of liner will not be interposed between the corner of the spike and the fillet in the corner of the hole in the plate, which condition, if allowed to exist, would make it almost impossible to drive the spike down through the hole. Such clearance is clearly shown in Fig. 7. Furthermore, if no slit were provided, the sides of the liner could, with utmost difficulty only, be positioned against the sides of the hole in the plate.

Due to the slit or slot, the edges of the sides of the liner adjacent to the slit or slot are positioned to clear the fillet and to present minimum obstruction to the passage of the corner of the spike which, as it is driven down, acts to properly position the sides of the liner to lie against the sides of the hole in the tie plate and to clear the corner fillet.

The bar portion of the metal beneath the slit or slot should be of minimum depth practical in the stamping process but must be of sufficient strength to position the sides of the liner during the driving of the spike, at least until frictional contact between the sides of the liner and the sides of the hole in the tie plate is sufficient to prevent displacement of the liner. If desired, the bar portion may be flattened so as to interpose minimum metal between the fillet and the corner of the spike.

As driving of the spike is continued, the ductile metal of the wings 41 and 42 may be compressed lightly and deformed to cause the wings to follow the exact inclina-

tion of the rough, uneven sides of the aperture and to cause the metal to flow so as to compensate for the irregularities in the punched hole. The result of this action is to produce a tight fit of the tapered shank portion 38 of the spike in the aperture 30 or 31 which is so effective that the tie-plate and spikes are practically joined in an integral structure. Consequently, the tie-plate 26 is secured fast to the tie 25 to guard against vertical or lateral movement of the plate. Since pivoting or oscillation of the spikes relative to the tie-plate is prevented, it follows that the spikes will remain securely fastened within the tie to prevent enlargement of the holes in the tie.

It is important that upward flexing of the rail 20 be permitted in response to the wave motion imparted thereto as the railway cars travel along the track. As shown in Fig. 3, the head 37 of the inner spikes overlie the longitudinal edges of the rail base 21 in spaced relation thereto to permit such undulation of the rail. In order to maintain this relation, the upper end 43 of the longer wing 42 underlies the head 37 and as the spike is driven, a sloping surface on the spike head acts to cam the end 43 over the rib 28 which then serves as a stop to limit further downward movement of the spike head, as illustrated in Fig. 4.

Referring now to Fig. 9, it is within the concept of this invention to provide a filler element 40' of alternative form which is similar to that shown in Fig. 9 with the exception that the extension 43 is omitted.

In Fig. 10 is illustrated a liner element 50 of further modified structure. This element has three sides 51, 52 and 53, each having an angularly bent ear or tab 54 at its upper end. It is to be observed that the intermediate side 52 is doubled back upon itself so that it is of twice the thickness of each of the other sides 51 and 53. The element is stamped from sheet metal of a thickness substantially equal to one-half of the clearance between the width of the aperture 30 or 31 and that of the spike. Consequently, when the element 50 is placed in an aperture it reduces the lateral dimensions thereof to substantially that of the tapered shank portion 38 as illustrated best in Fig. 11. Stated another way, the two sides 51 and 53 together take up the play between the spike and the aperture 30 in one direction while the side 52 of double thickness serves the same purpose in the other direction. It is thus seen that the effective dimensions of the square hole are reduced to substantially those of the spike so that when the latter is driven through the aperture, it will be firmly gripped therein to prevent loosening of the spike in the tie.

In accordance with the provisions of the patent statutes I have herein described the principle of the invention, together with the structures which I now consider to represent the best embodiments thereof. I wish to have it understood, however, that various modifications might be made in the structure of the filler or liner means without departing from the spirit or scope of the invention as defined in the appended claims.

I claim as my invention:

1. In combination with a railway tie-plate for mounting upon a tie and having a square downwardly convergent aperture through which a spike of square cross section and having a downwardly convergent shank is driven into the tie: a filler element insertable in the aperture and having two wings each placeable against a side of the aperture, said wings being of such thickness as to reduce the effective area of the aperture to substantially the cross-sectional area of the spike so as to effect a tight fit of the spike in the aperture, said wings being integrally joined one to the other adjacent their lower terminal ends.

2. In combination with a railway tie-plate for mounting upon a tie and having a square downwardly convergent aperture with filleted corners through which a spike of square cross section and having a downwardly

convergent throat is driven into the tie; a ductile, sheet metal filler element insertable in the aperture and having two flat, vertically disposed right-angularly related and integrally connected wings each placeable against a side of the aperture, said wings being of such thickness as to reduce the effective area of the aperture to substantially the cross-sectional area of the spike so as to effect a tight fit of the spike in the aperture.

3. A filler element as defined in claim 2 in which the sheet metal at the intersection of said integrally connected wings is slit longitudinally of said intersection to accommodate the adjacent filleted corner of the aperture and allow for free bending of the wings relative to each other in response to driving of the spike through the aperture.

4. A filler element as defined in claim 3 in which one of said wings has a laterally outwardly bent tab at its upper end to engage the top of the plate and maintain the said element in position in the aperture prior to insertion of the spike.

5. A filler means for use in connection with a railway tie-plate having a square downwardly convergent hole with filleted corners therein for receiving the square shank of a spike having a downwardly convergent shank, there being lateral clearance between the hole and spike shank consisting of a unitary filler element constructed from sheet metal of a thickness substantially equal to said clearance, said element having two integrally connected right-angularly related wings each having a width slightly less than the width of said spike hole, one wing having a laterally outwardly bent tab at its upper edge to engage and rest on the top of the plate and the other wing projecting above said tab, said element having a slit extending downwardly from the top lengthwise along the intersection between said wings and terminating above

the lower edge of the element and adapted to accommodate the adjacent filleted corner in the hole, the upper portions of said wings divided by said slit being bendable relative to each other.

- 5 6. A filler means for use in connection with a railway tie-plate having a square downwardly convergent hole therein and through which the square downwardly convergent shank of a spike extends, said hole being of greater cross-sectional area than that of the spike shank, said hole having rounded corners providing arcuate fillets, said filler means consisting of a unitary ductile, sheet-metal filler element of a thickness substantially equal to the lateral clearance between the hole and shank, said element having two integrally connected right-angularly related vertical sides, the intersection of said sides having a slit extending downwardly from the upper end of the element and terminating at a point in proximity to the lower end of the element, the width of said slit being equal to at least the chordal distance across a said fillet, 10 each side of the element being adapted to lie along a side of said hole and said sides being bendable relative to each other, each side of the element being of a width such that its vertical edge disposed remotely from said intersection terminates short of the adjacent fillet of the 15 spike hole.
